UNITED STATES PATENT OFFICE.

ROBERT C. ALLEN, OF SWARTHMORE, PENNSYLVANIA, ASSIGNOR TO WESTINGHOUSE ELECTRIC & MANUFACTURING COMPANY, A CORPORATION OF PENNSYLVANIA.

TURBINE SUPPORT.

Application filed November 4, 1925. Serial No. 66,833.

My invention relates to elastic fluid turbines, and it has for an object to provide means for supporting a turbine which shall minimize difficulties due to the expansion of the casing of the turbine when heated.

More specifically the object of my invention is to provide an improved supporting means for an elastic fluid turbine which shall permit free expansion of the turbine casing when heated, while maintaining the longitudinal axis of the turbine in the same vertical plane.

Apparatus embodying features of my invention is illustrated in the accompanying drawings forming a part of this specification, in which Fig. 1 is a plan view of a turbine foundation having my improved supporting means thereon; Fig. 2 is an end elevation of the low pressure end of an elastic fluid turbine mounted on the foundation shown in Fig. 1; Fig. 3 is an end elevation of the high pressure end of the turbine illustrated in Fig. 2; Fig. 4 is a plan view of a foundation adapted for a double flow turbine and having my improved supporting means applied thereto; Fig. 5 is a side elevation, partly in section, of a double flow turbine mounted on the foundation shown in Fig. 4; Figs. 6 and 7 are views in plan and elevation respectively of a supporting member made in accordance with my invention; Fig. 8 is a plan view of a sole plate in a modified form of the invention; and Figs. 9 and 10 are elevational views showing the opposite ends of the modified form.

It is well known in connection with elastic fluid turbines, especially those of large size, that a certain freedom of movement must be permitted between the turbine casing and the foundation or sole plate on which it is supported in order that free expansion of the casing when heated may occur, otherwise distortion may arise which is liable to cause misalignment of the shaft and rubbing of the turbine rotor or blades against the interior of the casing or other difficulties. In order to allow for expansion, it has been customary to fix the casing at some point along a line perpendicular to its longitudinal axis, permitting expansion away from said fixed point by slid-

ing along the foundation or sole plate, and to provide constraints or guides to maintain the longitudinal axis of the turbine in the same vertical plane. In permitting expansion away from the fixed point of the casing the friction between the casing and the sole plate may be excessive. It has been found, in this connection, with very large casings, that the constraints or guides provided are not sufficient to guide the casing so that movement of the longitudinal axis of the casing has occurred in a direction inclined to the vertical central plane of the turbine and consequent rubbing of the rotor on some part of the casing has, at times, occurred.

In accordance with my invention I overcome the beforementioned difficulties by fixedly securing the turbine casing at one point in the vertical plane of the longitudinal axis of the turbine, and constraining the casing so as to maintain the longitudinal axis of the turbine in the same vertical plane, as in previous installations. In addition thereto, I provide supporting members for the sides of the turbine casing provided with curved bearing surfaces so that the casing is free to expand laterally or longitudinally or both, with perfect freedom and practically without friction so that danger of moving the longitudinal axis of the turbine outside of its original vertical plane is eliminated.

Referring now to the drawings for a more detailed description of my invention I show in Fig. 1 at 10 a sole plate or foundation for a turbine. At each corner of the sole plate is disposed a supporting member 11, the surface of said supporting members being spherical, the circumference of said sphere being indicated by the dot and dash lines 12-12 in Figs. 6 and 7. The supporting members 11-11 may be retained in position by suitably formed bosses 13-13 if desired. At 14 is shown a hole, centrally located with respect to the longitudinal axis of the turbine, for the reception of a dowel pin 22, Fig. 2, for holding one end of the turbine casing in a fixed position and for maintaining the longitudinal axis centrally at that end of the turbine. In the drawing the dowel is indicated at the low pressure end of the turbine to be mount-

ed thereon though it will be obvious that it may well be at the opposite end of the turbine. At the opposite end of the foundation or sole plate 10 is formed a key or guide 16 adapted to fit into a cooperating slot on a turbine casing, permitting the casing to freely slide longitudinally of the turbine but maintaining its longitudinal axis central.

Referring now to Fig. 2 I show the low pressure end of a turbine 17 mounted upon the sole plate 10. Formed upon the end of the turbine casing is a suitable boss 18, said boss having provided thereon bearing surfaces 19-19, one at each side thereof and cooperating with the supporting members 11-11. The sole plate or foundation 10 is likewise provided with bearing surfaces 21-21 for cooperating with the supporting members 11-11. At 22 I show a dowel pin 20 inserted in the hole 14 of the sole plate 10 and also in a similar cooperating hole 23 formed in the boss 18 of the turbine casing. It may thus be seen that the low pressure end of the turbine casing is fixedly held by the centrally located pin 22 but is free to expand away from said pin, being supported by the members 11-11. The members 11-11 provide, in effect, ball bearings as well as supports for the casing so that it has perfect freedom of expansion away from the central point determined by the dowel pin 22.

Referring now to Fig. 3 I show the high pressure end of the turbine which is similar to the low pressure end in all respects save that the key 16 formed upon the sole plate or foundation 10, fits into a suitable guide 26 formed in the lower part of the boss 18. The turbine casing may expand away from the dowel pin 22 in all directions due to the spherical bearing surfaces of the members 11-11 but its longitudinal axis is maintained in the same vertical plane by means of the dowel pin 22 and the key and slot connection 16-26.

In Fig. 4 I show a sole plate or foundation 27 adapted to support a turbine of the double flow type exhausting at each end of the turbine casing. In accordance with this modification the bearings members 11-11 are provided at the four corners of the sole plate or foundation 27 as previously illustrated, but instead of fixedly retaining the casing at one end thereof as in the previous modifications, I provide a hole 28 centrally of the sole plate or foundation 27 for the reception of a dowel pin. At each end of the sole plate or foundation 27 is provided a key or guide member 29 for permitting free expansion of the casing as may better be seen by reference to Fig. 5. In Fig. 5 I show a double flow turbine 31 supported upon the sole plate or foundation 27 by the bearing members 11-11. The casing of the turbine 31 is dowelled to the sole plate 27 by means of a pin 32 in the hole 28 and is left free to expand away from said pin

by reason of the bearing members 11-11 at the ends of the casing. It is constrained by the keys 29-29 so as to maintain the longitudinal axis of the turbine in its original vertical plane.

In Figs. 2 and 3 it will be noted that the supporting members 11-11 are made comparatively short and that the bosses 18-18 formed upon the ends of the turbine casing extend downwardly below the center line 75 of the casing. In such an installation, if the bosses 18 become heated and expand it might cause a raising of the longitudinal axis of the turbine above the horizontal plane it occupies when cool. In accordance with the modification shown in Fig. 5, however, I provide bosses 33-33 at the ends of the turbine casing so arranged that the bearing surfaces for the supporting members 11 occur near the horizontal plane of the turbine axis. The 80 supporting members 11-11, being largely remote from the turbine casing, are not greatly influenced by the heat thereof and as the turbine casing expands the spherical surfaces of the supporting member maintain the casing 85 at the same height.

Referring now to Figs. 8, 9 and 10 I show a modified form of my invention wherein a sole plate 40, Fig. 8, has mounted thereon a turbine 41, Figs. 9 and 10. Secured to the 90 sole plate 40, at one end of the turbine 41, is a plate 42 which extends a sufficient distance beyond the center line of the sole plate 40 to accommodate a pin 43 which coacts between the plate 42 and a boss 44 and serves to anchor 100 one end of the turbine. The plate 42 is rigidly secured to the sole plate 40 as by a plurality of bolts 46-46 so that longitudinal movement of the pin 43 is prevented. The opposite end of the turbine may be held substantially 105 central by means of a link 47 secured to the turbine, near its center line, by means of a pin 48 and to the sole plate 40 by means of a pin 49. The turbine is supported at its four corners by means of the bearing members 11-11 as shown in the previously described 110 modifications, which permit freedom of movement of the turbine casing upon expansion away from lines of constraint. With this modification of my invention, when the turbine expands longitudinally the pin 48 moves in a small arc of a circle described by the rod 47 as a radius. The movement away from the center line of the turbine is so small, however, as to be inconsequential.

From the foregoing it will be apparent that I have invented an improved support for an elastic fluid turbine effective to maintain the longitudinal axis of the turbine in a central vertical plane and in the same horizontal 125 plane while permitting freedom of expansion upon heating of the casing.

While I have shown my invention in several forms, it will be obvious to those skilled in the art that it is not so limited, but is sus- 130

ceptible of various other changes and modifications, without departing from the spirit thereof, and I desire, therefore, that only such limitations shall be placed thereupon as are imposed by the prior art or as are specifically set forth in the appended claims.

What I claim is:—

1. Means for supporting a turbine comprising spherically surfaced bearing members at each end of the turbine for supporting the weight thereof, a centrally located fixed retainer at one end of the turbine and a centrally located sliding connection between the turbine and the stationary member at the opposite end.

2. The combination of a turbine having a casing, a foundation, suitably formed bearing surfaces provided on the casing and on the foundation, and spherically surfaced supporting members between the bearing surfaces.

3. The combination of a turbine having a casing, a foundation, suitably formed bearing surfaces provided on the casing and on the foundation, spherically surfaced supporting members between the bearing surfaces, means for fixedly retaining the turbine at one point, and means permitting longitudinal expansion away from said point while maintaining the longitudinal axis of the turbine in its original vertical plane.

4. The combination of a turbine having a casing, a foundation for the turbine, bearing surfaces provided on the foundation and on the casing at each end of the turbine, supporting members interposed between the bearing surfaces on the turbine casing and on the foundation respectively, and means for fixedly retaining the turbine to the foundation at one point.

5. The combination of a turbine having a casing, a foundation for the turbine, bearing surfaces provided on the foundation and on the casing at each end of the turbine, supporting members interposed between the bearing surfaces on the turbine casing and on the foundation respectively, means for fixedly securing the casing to the foundation at one point and means for centrally maintaining the longitudinal axis of the turbine at other points.

6. The combination of a turbine having a casing, a foundation, bosses provided on each end of the turbine and extending transversely thereof, said bosses having bearing surfaces provided thereon, cooperating bearing surfaces provided on the foundation, supporting members having curved surfaces interposed between the bearing surfaces of the bosses and the foundation, means for fixedly retaining the turbine casing at one point, and guide means for maintaining the longitudinal axis of the turbine in the same vertical plane at other points.

7. The combination of a turbine having a

casing, bosses provided on the ends of the turbine casing and extending transversely thereof, said bosses having bearing surfaces provided thereon at each side of the turbine, members having cooperating bearing surfaces supported from the foundation, supporting members having curved surfaces interposed between the bearing surfaces of the bosses and the foundation, a centrally located dowel disposed between the turbine casing and the foundation at one end of the casing for fixedly locating said portion of the casing, and a centrally located sliding key connection between the opposite end of the casing and the foundation for maintaining the longitudinal axis of the turbine in its original vertical plane and permitting freedom of longitudinal expansion.

8. The combination of a turbine having a casing, a supporting means, a suitably formed bearing surface provided on the casing and on the supporting means, and a rocking supporting member between the bearing surfaces, said bearing surfaces and said rocking supporting member being formed to permit movement in any horizontal direction of said casing at the bearing surface provided thereon.

9. The combination of a turbine casing having a horizontal downwardly facing plane surface, a stationary supporting structure having a horizontal upwardly facing plane surface, a rocking supporting member disposed between said surfaces, said supporting member having curved surfaces formed about a common center and contacting with both of said plane surfaces.

10. The combination of a turbine casing having a horizontal downwardly facing plane surface, a stationary supporting structure having a horizontal upwardly facing plane surface, a rocking supporting member disposed between said surfaces, said supporting member having curved surfaces forming part of a common sphere and contacting with both of said plane surfaces.

11. The combination of a turbine having a casing, a supporting means, a suitably formed bearing surface provided on the casing and on the supporting means, and a rocking supporting member between the bearing surfaces, said supporting member maintaining rolling contact with one of said bearing surfaces upon horizontal movement of said casing at its bearing surface.

12. The combination of a turbine having a casing, a stationary supporting structure, a suitably formed bearing surface provided on the casing and on the supporting structure, and a rocking supporting member disposed between the bearing surfaces, said rocking supporting member maintaining rolling contact with said bearing surfaces upon horizontal movement of said casing at its bearing surface.

13. The combination of a turbine casing having a downwardly facing bearing surface, a stationary supporting structure having an upwardly facing bearing surface, and 5 a rocking supporting member disposed between said bearing surfaces and maintaining rolling contact therewith upon horizontal

movement of said casing at its bearing surface in any horizontal direction.

In testimony whereof, I have hereunto 10 subscribed my name this twenty-ninth day of October 1925.

ROBERT C. ALLEN.
